UNITED STATES PATENT OFFICE.

ALFRED J. SIGNOR, OF ELKHART, INDIANA, ASSIGNOR OF ONE-HALF TO
FREDRICK L. CALLINS, OF SAME PLACE.

DIE-STOCK.

SPECIFICATION forming part of Letters Patent No. 256,448, dated April 11, 1882.

Application filed June 28, 1881. (Model.)

To all whom it may concern:

Be it known that I, ALFRED J. SIGNOR, of Elkhart, in the county of Elkhart and State of Indiana, have invented certain new and useful 5 Improvements in Die-Stocks for Cutting Screw-Threads; and I do hereby declare the following to be a full, clear, and exact description of the invention, such as will enable others skilled in the art to which it pertains to make and 10 use it, reference being had to the accompanying drawings, which form part of this specification.

My invention relates to an improvement in die-stocks for cutting screw-threads; and it consists in pivoting one of the handles by 15 which the die is operated in one end of the frame in which the dies are placed, and forming a cam and a stop upon the end of this pivoted handle, whereby the two parts of the dies can be forced together with any desired degree 20 of pressure, and the pivoted lever be prevented from moving past the center, as will be more fully described hereinafter.

The object of my invention is to provide a die-stock for cutting screw-threads, in which 25 one of the handles by which the die is operated can be utilized in forcing the dies together with any desired degree of pressure, and which handle is made removable from the plate, so that the tool can be packed into 30 smaller space.

Figure 1 represents a plan view of my invention. Fig. 2 represents a vertical section of the same with the pivoted handle turned at right angles. Fig. 3 is a perspective of the 35 upper part of the die-stock.

A represents the plate or frame, in which the two parts B C of the die are placed. Both of these parts of the die have a suitable groove formed in their sides, for the purpose of catching 40 over corresponding projections which are made upon the inner edges of the frame A. The upper part of this die has a portion of one of its sides cut away, as shown, so that it can be readily removed whenever so desired. These 45 two parts of the die are adjusted back and forth in relation to each other, and one of them is adjusted by means of the screw-handle D, which passes through one end of the frame A, and bears against it, while the other part of 50 the die is operated by the cam J, which is formed upon the inner end of the pivoted

handle H. This handle H is pivoted in the open end of the frame upon the bolt I, and for the purpose of preventing this handle from moving beyond a straight line with the frame 55 when the handle is being moved into position, it is provided with a flange, L, which catches against one of the parts of the die, and thus acts as a stop. The cam formed on the end of this pivoted handle serves to force the part of 60 the die which is next to it toward the other part of the die, and to lock the two rigidly in position. Neither one of these parts of the die can be removed from the frame until the pivoted handle has been turned at right 65 angles to the frame, as shown, so as to raise the cam out of the way. After the handle has been turned, as shown in Fig. 2, the two parts of the die can be moved toward this pivoted handle and removed through the cut-away 70 portion, as shown. Should the cam not be sufficient to force the two parts of the die closely enough together, the other handle can be turned so as to force them as near together as may be found necessary. By means of this 75 construction the two parts of the die can be readily removed from the frame by simply turning the pivoted handle at right angles, and then moving the two parts of the die to the cut-away portion, and thus different dies can 80 be used at will. The handle, being pivoted, can also be removed, so that the tool can be packed in less space.

I am aware that a frame having a lever or handle pivoted in one end and having a cam 85 on its inner end to force the two dies together is not new, and this I disclaim.

Having thus described my invention, I claim—

In a die-stock, the frame A, open at one end, 90 and having pivoted in this open end a lever, H, which has the cam J and stop L formed upon its inner end, in combination with the screw-threaded handle, and dies, substantially as shown. 95

In testimony whereof I affix my signature in presence of two witnesses.

ALFRED J. SIGNOR.
